ATTORNEY

UNITED STATES PATENT OFFICE

MILTON C. STERN, OF DAYTON, OHIO, ASSIGNOR TO THE EGRY REGISTER COMPANY, OF DAYTON, OHIO, A CORPORATION OF OHIO

PAPER SUPPLIES

Application filed December 30, 1929. Serial No. 417,409.

My invention relates to manifold stationery in which a plurality of copies are desired.

The primary object of my invention is to provide an article of manufacture for duplicating identical data simultaneously and for a rapid detachment of the sheets written upon and the carbon interleaves.

My invention is adaptable to a variety of uses, such as in autographic registers, billing machines, typewriters and other equivalent mechanism.

It is a further object of my invention to provide such an arrangement of paper and carbon strips that they will be easily retained in their predetermined relationship, will not need any special formation of paper strips or carbon strips and all clipping, punching or other mutilation of the respective strips will be avoided which have heretofore been employed for the purpose of selectively separating the strips.

Furthermore, my invention is adaptable to being applied at the time the paper strips are correlated, preferably with printed forms upon them as they pass from the printing press, thus enabling my invention to be adapted and the results secured without the necessity for special machinery and without disturbing the regular productive processes now in effect in industries and in offices or other commercial practice.

In particular, it is my object to provide means of grasping the paper strips with one hand and the carbon strips with the other and being able to pull them by a natural movement apart without tearing or smudging and with a broad, firm foundation for the grip on the respective groups of strips. The sheets are so arranged that one hand always grasps the carbons, if desired, thereby leaving the other hand not only free but clean for manipulating the paper strips. The tips of the fingers need not be employed and thereby the objection to handling the carbon sheets with the tips of the fingers is avoided due to the accumulation of carbon particles beneath the finger nails.

Referring to the drawing:

Figure 1 is a perspective of a portion of a

length of superimposed strips and interleaved carbons arranged according to my invention with the free ends thereof turned back to disclose the peculiar arrangement of the respective groups of strips which characterize my invention;

Figure 2 is a section on the line 2—2 of Figure 3;

Figure 3 is a plan view partially broken away at one end and turned back in successive layers at the other end of a length of superimposed paper and carbon strips.

In practicing my invention I provide a plurality of superimposed paper strips 1, 2 and 3. Of course, any number may be employed, for these strips are all aligned laterally with respect to one another and directly superimposed with one another. Interleaved between said strips and longitudinally co-extensive therewith are a plurality of strips of substantially the same width of carbon or other reproducing medium designated 4 and 5. These strips with respect to themselves are superimposed in direct lateral alignment, but as a group are bodily displaced laterally so that their edges 6 and 7 project beyond the edges 8, 9 and 10 which are adjacent thereto and form the edges of the sheets 1, 2 and 3. The other edges of the carbon 4 and 5, which edges are designated 11 and 12 are spaced inwardly within the edges 13, 14 and 15 of the paper sheets which strips hide the edges 11 and 12 of the carbon strips.

This arrangement results in the carbon strips projecting as a group along one edge beyond the edges of the paper strips and on the other side projecting as a group beyond the carbon strips.

In practice the operator when desiring to separate the two groups of strips after they have been ejected from a machine or torn off the pack, will grasp the carbon strips with one hand and the paper strips with the other pulling them apart by an outward movement transverse to the length of the strips, thus readily separating them. All of the carbon strips will move as a group to the one side and all of the paper strips as a group will move to the other side. As the free margins of the respective groups of strips as grasped by the

hands of the operator do not have any portion of the strips therebetween there is no resistance to this movement and no necessity for any selective operation by hand.

5 It will be understood that I desire to comprehend within my invention such modifications as may be clearly embraced within the scope of my claims and invention.

Having thus fully described my invention,
10 what I claim as new and desire to secure by Letters Patent, is:

1. In combination, superimposed, laterally aligned paper strips and interleaved carbon strips projecting laterally thereof in a marginal strip, said carbon strips having the other side thereof spaced inwardly of the other edge of said superimposed paper strips.

2. In combination, a plurality of longitudinally arranged superimposed paper and carbon strips, longitudinally aligned in respective groups of paper strips and carbon strips and laterally displaced relative to one another as a group whereby the paper margins free of the carbon strips will be provided on 25 one side and the carbon margins free of the paper strips will be provided on the other side.

3. In combination, a plurality of superimposed, aligned paper strips, coinciding with 30 one another longitudinally, and a plurality of interleaved alternate carbon strips coinciding with one another longitudinally but off set as a group laterally in one direction from the paper strips which are offset laterally in the 35 other direction forming respective marginal strips of one group only on one margin.

4. Continuous record strips in superimposed relation and a transfer strip between 40 adjacent record strips, one longitudinal margin of the transfer strip projecting beyond contiguous longitudinal margins of the record strips, opposite longitudinal marginal portions of the transfer strip being inset with respect to adjacent marginal edges of the record 45 strips.

In testimony whereof, I affix my signature.
MILTON C. STERN.
